UNITED STATES PATENT OFFICE.

JOSEPH A. MOORE, OF LOUISVILLE, KENTUCKY.

IMPROVEMENT IN PLOWS.

Specification forming part of Letters Patent No. **59,437**, dated November 6, 1866.

To all whom it may concern:

Be it known that I, JOSEPH A. MOORE, of Louisville, in the county of Jefferson, and in the State of Kentucky, have invented a new and useful Improvement in Plows; and do hereby declare that the following is a full, clear, and exact description thereof.

Figure 1 is a perspective view of mold-board. Fig. 2 is a view showing the handle fast to mold-board. Fig. 3 is a cross-section through fastening-bolts.

My invention relates to an attachment of the mold-board handle to the under side of the mold-board without passing the bolts that secure the same through the mold-board.

My invention consists in using a slotted flange, A, cast on the under side of the mold-board B, projecting outward therefrom, to which the mold-board handle C is firmly and securely attached. The bolts D are passed through the slots in the flange, which slots are so adjusted as to tend toward a common center, thus giving mutual support and prevent-

ing the possible detachment of the bolts, as more fully appears by reference to the drawings, and presents a continued bearing for the handle almost the entire length of the mold-board, thus securing great strength of attachment.

My invention being intended more especially for cast-plows secures great facility of casting the same. The pattern, being divided in the center between the two slots, thus requires only two pieces to be drawn from the mold to insure a perfect casting of the same.

What I claim as my invention, and desire to secure by Letters Patent, is—

The slotted flange made as described, as and for the purpose set forth.

In testimony that I claim the above-described improvement in plows I have hereunto signed my name this 7th day of September, 1866.

JOSEPH A. MOORE.
